UNITED STATES PATENT OFFICE.

SAMUEL LOREE, OF CINCINNATI, OHIO, ASSIGNOR OF ONE-HALF TO JOHN LOREE, OF LINCOLN, NEBRASKA.

COMBINED CORN SHELLER AND CUTTER.

SPECIFICATION forming part of Letters Patent No. 443,143, dated December 23, 1890.

Application filed June 28, 1890. Serial No. 356,900. (No model.)

To all whom it may concern:

Be it known that I, SAMUEL LOREE, a citizen of the United States, residing at Cincinnati, in the county of Hamilton and State of Ohio, have invented certain new and useful Improvements in Combined Corn Shellers and Cutters; and I do hereby declare the following to be a full, clear, and exact description of the invention, such as will enable others skilled in the art to which it appertains to make and use the same.

My invention consists in the improved form of combined corn sheller and cutter herein-after to be more particularly described and claimed.

In the drawings, Figure 1 is a side view of the machine. Fig. 2 is a plan view. Fig. 3 is a vertical central section. Figs. 4, 5, and 6 are detail views of one of the shelling-knives. Figs. 7 and 8 are similar views of one of the corn-cutting knives. Fig. 9 is a detail side view of one of the guide-rollers and its support, and Fig. 10 is a plan view of the same.

Heretofore various kinds of corn-shelling machines have been devised, but nearly all of them are bulky, and require considerable power to run them. Various kinds of apparatus have also been designed for cutting corn from the cob when green, for canning and other purposes.

To construct a single and simple machine of small size, which by slight change of parts can be used either as a corn-sheller or a corn-cutter, I have devised the construction shown and illustrated, in which—

A is the main frame, which may be attached to the side of a tub or to any other object by means of the forked ends $a' a''$ and the set-screw B. This frame A is expanded in the form of a ring a , as shown in Fig. 2, and also has a vertical projection in which the beveled driving-wheel W, having the crank-arm K, is journaled.

The main operative portion of the machine consists of the knife-carrying ring D, (best shown in Figs. 1 and 3,) which is mounted on the main frame by means of the cleats H, which are attached to the ring D by the screws h or in any similar equivalent manner, and which overhang the projecting ring

or ledge a''' of the main frame, and thereby act as a bearing on said main frame, at the same time permitting the revolution of the ring D. There may be three or more of these cleats H; or, if desirable, they might be all connected together in one solid ring, as will be easily understood, without varying the nature of the construction.

On the knife-carrying ring D are cast proper bevel-teeth d , which gear with those w on the bevel driving-wheel W. In said ring are mounted in any suitable manner a number of knives, as N or M, which converge to the center and bear against and operate upon the ear of corn. Said knives are given a suitable inclination all in one direction, so that as they operate upon the ear of corn they also draw the cob down or up through the machine, according to the manner in which they are set. My preferred construction of said knives is clearly illustrated in Figs. 4 to 8, inclusive, where is shown the main shank S of each knife and one or more guide projections G G', which run in openings in the ring D, as clearly shown in Fig. 3, and prevent the knives from turning.

In the cavity F in the knife-carrying ring and surrounding the shank S of the knife is a spiral spring P. This acts against the flange E on the knife-shank and tends to force it away toward the center of the machine, the projection of the knife in this way beyond a certain point being prevented by an adjustable nut s, affixed at the end of the shank S.

C is a supporting-ring of equal diameter to that of D, and held beneath the same by means of the projection C', which terminates in a suitable foot and is adjustably and removably held to the main frame A by means of bolts c c, as clearly shown in Figs. 1 and 2. This supporting-ring C affords an additional support for the knife-carrying ring D, and also carries the guide-rollers R, of which there are three or more converging to the center of the ring and closing on the ear of corn to guide and steady the same in its passage through the machine. These guide-rollers may evidently be made in a number of shapes and supported in any suitable manner. The preferred construction, however, is that which

I have illustrated in Figs. 9 and 10, where the rollers R are shown with double flanges $r r'$ for grasping the ear of corn, and are mounted in a support Q, which has a shank T and 5 guide projections $t t'$. This support Q is mounted in the ring C in a manner similar to that in which the knives are mounted in the ring D, as above described. The spiral springs P' act to force the rollers out against 10 the ear of corn.

The mode of operation of my invention is evident. If an ear of ripened corn is to be shelled, the knives N N N are placed in the machine, as shown in Figs. 2 and 3. One end 15 of the ear of corn then being introduced between said knives, rotation is given to the ring D by means of the crank and the handle shown. The action of the knives is to rip the kernels of corn from the cob, and at the same 20 time, on account of their curvature and inclination, a feed motion is given the ear onward through the machine, it being steadied meantime by the guide-rollers R. By the time the ear is passed through the operator 25 has another one ready to introduce, and the operation of the machine is thereby practically continuous.

When it is desired to cut green corn from the cob, the knives N are removed and the 30 sharper knives M, of greater curvature, are introduced in their places. Otherwise the operation is the same.

It is evident that numerous changes in the details of construction and arrangement might 35 be made from the above-described apparatus without departing from the spirit of my invention, or the principle of operation herein described, such changes being mere mechanical changes still within the scope of my in- 40 vention.

Having therefore described my invention, what I claim as new, and desire to protect by Letters Patent, is—

1. In a corn sheller and cutter, the combination of the main frame having a ring portion, the knife-carrying ring mounted and revoluble on said frame, the knives mounted in said latter ring, annular frame or ring for supporting the knife-carrying ring adjustably 45 attached to the main frame, and gearing for revolving the same, substantially as described.

2. In a corn sheller and cutter, the combination of the main frame, the knife-carrying ring mounted and revoluble on said frame, the knives mounted in said latter ring, annular frame or ring for supporting the knife-carrying ring adjustably attached to the main frame, and gearing for revolving the same, together with the guide-rollers mounted in the supporting-ring, substantially as described.

3. In a corn sheller and cutter, the combination of the main frame, the knife-carrying ring which is mounted and revoluble on said frame and which has bevel-teeth cast thereon, 6 the inclined knives mounted in said ring, the annular frame or ring supporting the knife-carrying ring removably attached to the main frame, and the crank and bevel-gear mounted on said frame and gearing with the above- 7 mentioned teeth on the knife-carrying ring, substantially as described.

4. In a corn sheller and cutter, the inclined curved knives, each of which has a three-pronged shank, and a spiral spring connected 7 therewith, substantially as described.

5. In a corn sheller and cutter, the combination of the main frame, the knife-supporting ring, the inclined curved knives mounted in said ring, having three-pronged shanks, and 8 spiral springs connected therewith, substantially as described.

6. The combination of the double-flanged roller, the three-pronged support for the same, the spiral spring, and the ring in which said 8 supports are mounted, substantially as described.

7. In a corn sheller and cutter, the combination of the main frame, the knife-carrying ring mounted and revoluble on said frame, 90 the curved spring-pressed knives mounted in said ring and converging to the center thereof, the removable annular support for the knife-carrying ring, gearing for giving rotary motion to the knife-carrying ring, and the 95 double-flanged spring-pressed guide-rollers mounted in the supporting-ring, substantially as described.

In testimony whereof I affix my signature in presence of two witnesses.

SAMUEL LOREE.
